RAILROAD CROSSING

Benjamin Cullen Monroe, Tuscola, Ill.

Application September 19, 1938, Serial No. 230,554

4 Claims. (Cl. 246—380)

Heretofore when two railway lines cross, the rails at the point of crossing are cut away in both directions to accommodate the flange of the car wheels with the result that a gap is made in each rail and a car wheel must drop into one of these gaps at each intersection of its rail with that of a cross rail. The hammering produced by the car wheel dropping into the gap at each intersection is destructive of the rails at this point and productive of a great deal of vibration and noise.

An object therefore of this invention is to provide a railway crossing with means for eliminating this gap in the direction the train is traveling to eliminate the attendant pounding, jar and noise.

This and other objects, as will hereinafter appear, are accomplished by this invention, which is fully described in the following specification and shown in the accompanying drawings, in which—

Figure 1 is a partial top plan view of a railroad crossing embodying the invention and showing a cover plate partly removed and with slides set so as to permit the rails to be used in a vertical direction;

Fig. 2 is a fragmentary view of the same showing the slides set in the reverse direction so as to permit the horizontal rails to be used;

Fig. 3 is a fragmentary view of the same showing one of the slides set in a mid-position so as to permit both the horizontal and vertical rails to be used;

Fig. 4 is a partial transverse vertical section on the line 4—4 of Fig. 1;

Fig. 5 is a partial enlarged vertical section on the line 5—5 of Fig. 2;

Fig. 6 is a partial enlarged vertical section on the line 6—6 of Fig. 3;

Fig. 7 is a partial enlarged vertical section on the line 7—7 of Fig. 1;

Figs. 8, 9 and 10 are views similar to Figs. 1, 2 and 3 respectively showing a modified form of the invention;

Figs. 11, 12, 13 and 14 are enlarged vertical sections on the lines 11—11, 12—12, 13—13 and 14—14 respectively of Fig. 8; and

Fig. 15 is a cross section of a modified form of rail.

The preferred embodiment shown in Figs. 1 to 7 comprises a crossing made up of rails 20 and 21, which for convenience are referred to as vertical rails, and rails 22 and 23, which are referred to as horizontal rails. These rails preferably have a cross section similar to that shown in Fig. 7. The crossing may be cast integral or may

be made up of sections riveted, bolted or welded together. It will also be understood that while the rails here shown are at right angles to each other, they may also be set at other convenient angles.

The rails at the point of intersection are cut through diagonally by a channel 24 (Fig. 6) at the upper portion to accommodate slides 25, 26, 27, 28. These slides as will presently be explained are operably connected together by a system of links and each slide is preferably provided with three recesses which are brought into juxtaposition with the grooves in the rails in various combinations to bridge the gap in the opposite rail. Thus the rails 20 and 21 are provided with a groove 20^a and 21^a (Figs. 1 and 7) and the rails 22 and 23 are provided with grooves 22^b and 23^b respectively. The slides 25 and 28 are provided with diagonal grooves 25^a and 28^a respectively which are adapted to register with the groove 21. Likewise, the slides 26 and 27 are provided with grooves 26^a and 27^a which at the same time are adapted to register with the groove 20^a of the rail 20. When in this position, power wheels can then run on the rails 20 and 21 while their flanges follow the grooves 26^a, 20^a and 27^a in one case and 25^a, 21^a and 28^a in the other case. It will thus be seen that the grooves 22^b and 23^b of the horizontal rails are at the same time bridged by these slides so that the usual jar of the wheel crossing these horizontal grooves is eliminated.

The slide 25 is preferably operated by means of a link 29 from a lever or the like not shown. This slide connects directly with the slide 27 by means of a link 30. The slide 25 also connects through a link 31 with a bell crank 32 which is pivotally mounted at 33 at the opposite end of the bell crank connecting through a link 34 with the slide 26, the latter connecting through a rod 40 with the slide 28.

Thus, an inward motion of the slide 25 causes the links 25, 26 and 28 to assume the position shown in Fig. 2. In this position, grooves 25^b and 26^b in the slides 25 and 26 register with the groove 23^b at the same time closing the grooves 20^a, 21^a in the vertical rails. Thus a train may now run over the horizontal rails, the slides 25 and 26 serving to carry the load of the wheels across the intersection on the same level so that the grooves 20^a, 21^a do not produce any jar.

Under some circumstances, it may be desirable to provide means on the slide for enabling trains to run either over the vertical rails or the horizontal rails without resetting. To accomplish

this, I have provided the slides with intersecting grooves in the form of a cross 25°, 26°, 27° and 28°. In a mid-position of the slides, these cross channels register with the grooves in both the 5 vertical and horizontal rails so that trains can readily run over the intersection in either direction.

A cover plate 36 is placed over the center of the crossing and is preferably secured as shown in 10 Fig. 7 by a series of bolts 36a or the like which screw into the lugs 38 which may be secured to the rails as by electric welding.

Each end of the crossing 23a (Figs. 2 and 5), 15 abuts a corresponding rail 37 and is secured thereto in any well known manner as by means of side plates 38 and bolts 39. The rail 37 is preferably carried on ties 40 while the crossing is preferably supported on a concrete base 41 which carries ties 42. A yielding means such as 20 plates 43 and 44 separated by suitable springs 45 provide a support which will yield about the same amount as the rail 37.

A space 46 (Fig. 4) is provided adjacent each 25 of the rail intersections which is covered by a swinging door 47. This may be raised to permit insertion of a torch 48 or the like which may be lighted to keep the intersection warm so as to be free from snow and ice whereby the 30 slides may freely operate even under adverse conditions. A space 49 (Fig. 6) is also provided beneath each of the slides to permit the passage of hot air and to permit any sand accumulating at this point to work out as the slide is operated. For this purpose, each slide is also provided with 35 a series of small grooves 50 to cause the sand and the like to work out as the slides are moved.

In Figs. 8 to 14, inclusive, is shown a modified form of the railway crossing in which the rails are preferably made up of flat slabs and secured together by means of bolts or rivets. For the 40 sake of clearness, many of these have been omitted. Thus the vertical rails 60 and 61 and the horizontal rails 62 and 63 are each made up of a number of vertically disposed flat slabs, 45 and the description of one of them will serve for all. Thus the rail 61 is made up of flat bars 64, 65, 66, 67 and 68 (see Fig. 11). These members are all stationary with the exception of the member 67 which is movable as will later be 50 shown. Where the rails cross each other, these members are let into each other as shown in Fig. 13 where the groups of four members making up the rail 60 and 61 are cut away at the lower half to enable them to pass the rail 63, the upper half of which is recessed.

The upper surfaces of members 66 and 67 serve as the rail on which the car wheels run, the depression between the members 64 and 68 and above the member 65 serving as a groove 60 to accommodate the flange of the car wheel. Beneath the member 67 is a strip 69 which is bolted or riveted to the members 64, 65 and 66 and provides a ledge on which the member 61 slides. This member 67 is operated by one arm 65 of a bell crank 70, operating through a suitable slot in the rail and which is pivotally mounted at 71 on a bracket 72 which is secured to the inner rail member 64. The bell crank also has an arm 73 which operates a similar sliding member 74. This bell crank is oscillated by means of a link 75 which is connected through a pin 76 with a block 77. This block is moved back and forth by means of an operating rod 78 which in turn is moved by a switch lever, not shown, 70 and which is provided with means for locking 75

it in either of its end positions or in an intermediate position, for a purpose which will presently appear. There are four bell cranks, one at each inner corner of the railway crossing and each bell crank operates two slide members as 5 67, 74, and 67a and 74a, etc.

In the position shown in Fig. 8, the slides 10 74 and 74a are drawn back so as to leave clear the groove over the members 65 and 65a in the vertical rails. At the same time, the slides 67 and 67a are moved so as to bridge the grooves 15 79 and 79a of the horizontal rails 62 and 63.

Thus, a wheel rolling on the vertical rails will roll on the outer ends of the slides 67, 67a, etc., across these gaps so as to transfer the load of 15 the wheel from the rail 66 to a rail 68a which is ordinarily separated therefrom by the width of the gap. Consequently the wheels will pass over this intersection without the usual pounding which is occasioned by the wheel dropping into 20 the gap in the intersection of the grooves.

In Fig. 9 is shown the same crossing with the bell cranks reversed so as to permit a train to run on the horizontal rails, the sliding members 25 here again bridging the gaps which occur in the vertical rails. In Fig. 10 the bell crank is shown in a mid-position wherein the grooves in both the vertical and horizontal rails are open so that trains could operate on both the vertical and horizontal rails. It will be understood that the 30 railway crossing lies in a horizontal plane or substantially so and that the words "vertical" and "horizontal" as used herein are for convenience only in designating the rails as shown in the drawings. The short slide members 67, 67a, etc., 35 are guided by the plates 38. The latter are cut away at the center to form a recess 68a and the inner ends of the slide members 67, 67a, etc., are beveled at their inner ends so as to force any sand accumulating on the support 69 toward the recess 68a where it will fall free of the rail. The member 68 also has a number of vertical slots 68b therein to enable sand and grit to drop out.

A space 80 (Fig. 11) is provided beneath the 45 member 69 for the insertion of a torch 81 and a door 82 is hingedly mounted to cover this space. This torch provides a means for heating this portion of the rail to melt snow and ice so as to insure the ready operation of the sliding members in stormy weather. A sheet metal 50 cover 83 is secured over the operating mechanism as by means of bolts 84 in lugs 85, the latter being preferably welded to the inner rail members.

In Fig. 15 is shown a modification of the rail 55 of Figs. 8 to 14 in which the rail members 64, 65, and 66 are replaced by an integral rail 86. This is provided with a series of sliding members 87 which rest upon a ledge 88 and are guided by said members 89 which are bolted to the rail section. The sliding members 87 are moved by means of bell cranks as before to cover and uncover the 60 gaps in the rails caused by the grooves at the intersection.

Thus it will be seen that I have provided a very 65 simple and efficient means for bridging these gaps thereby preventing the excessive pounding which occurs at rail intersections.

While I have shown and described but a few 70 forms of my invention, it is to be understood that it is capable of many modifications. Changes, therefore, in the construction and arrangement may be made which do not depart from the spirit and scope of the invention as defined by the appended claims.

I claim:

1. In a railway crossing of the class described, intersecting rails, each having grooves for the passage of flanges of railway wheels, the groove in one rail forming a gap in the intersecting rail, a member at each of the intersections, said members having grooves adapted to register with the grooves in either pair of rails and to fill the gaps in the other pair of rails to carry the car wheels over the latter gaps to prevent pounding, each member also having a single cross groove adapting the members to simultaneously register the several rail grooves of the crossing and means for simultaneously moving said members from one adjusted position to another to bring selected grooves of the members into effective registering positions.
2. In a railway crossing of the class described, intersecting rails, each having grooves for the passage of flanges of railway wheels, the groove in one rail forming a gap in the intersecting rail, a member at each of the intersections having grooves adapted to register with the grooves in either pair of rails and to fill the gaps in the other pair of rails to carry the car wheels over the latter gaps to prevent pounding, each member also having a single cross groove located between the first named grooves thereof and adapting the members to simultaneously register the several rail grooves of the crossing, and means for simultaneously moving said members to selectively bring the several grooves thereof into effective registering position.
3. In a railway crossing, a series of intersecting rails, each having grooves for the passage of the flanges of railway wheels, forming gaps at their points of intersection, a member at each of the points of intersection of the rails, said members having longitudinally spaced angularly disposed grooves and being movable to register said grooves with the grooves in either pair of intersecting rails and to fill the gaps in the other pair of rails, each member also having a single cross groove located approximately midway between its first mentioned grooves and each groove including intersecting angular portions adapting the members to simultaneously register the several rail grooves of the crossing, and means for moving said sections from one position of registration to another including connections between the members constraining the same to simultaneous movement.
4. In a railway crossing, a series of intersecting rails, each having grooves for the passage of the flanges of railway wheels, forming gaps at their points of intersection, a member at each of the points of intersection of the rails, said members having longitudinally spaced angularly disposed grooves and being movable to register said grooves with the grooves in either pair of intersecting rails and to fill the gaps in the other pair of rails, each member also having a single cross groove located approximately midway between its first mentioned grooves and each groove including intersecting angular portions adapting the members to simultaneously register the several rail grooves of the crossing, means for moving said members from one position of registration to another including connections between the members constraining the same to simultaneous movement, said connections between the members being disposed within the rail intersection, and a cover plate normally protecting the connections between the members, extending across the rail intersection and anchored to the rails.

BENJAMIN CULLEN MONROE.
